CLAIM

The ornamental design for a golf swing speed training equipment, as shown and described.

DESCRIPTION

FIG. 1 is a front elevation view of a golf swing speed training equipment showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

The dash-dot broken lines show portions of the golf swing speed training equipment and form no part of the claimed design.

1 Claim, 8 Drawing Sheets
